(57) CLAIM

The ornamental design for a tool holder bar, as shown and described.

DESCRIPTION

FIG. 1 is a front, left, top perspective view of a tool holder bar showing my new design;

FIG. 2 is a front view thereof;

FIG. 3 is a rear view thereof;

FIG. 4 is a top view thereof;

FIG. 5 is a bottom view thereof;

FIG. 6 is an enlarged left side view thereof; and,

FIG. 7 is an enlarged right side view thereof.

The broken lines in the drawings illustrate portions of the tool holder bar that form no part of the claimed design, except for the broken lines in FIGS. 1-5 that are marked with a bracket, which are for the purpose of illustrating portions of the tool holder bar with a symbolic break in its length. The appearance of any portion of the tool holder bar between the break lines forms no part of the claimed design.
